UNITED STATES PATENT OFFICE.

NETTIE M. HURD, OF CHICAGO, ILLINOIS.

HOSE-SUPPORTER.

1,374,572.

Specification of Letters Patent. Patented Apr. 12, 1921.

Application filed November 18, 1918, Serial No. 262,978. Renewed February 4, 1920. Serial No. 356,122.

To all whom it may concern:

Be it known that I, NETTIE M. HURD, a citizen of the United States, residing at Chicago, in the county of Cook and State of Illinois, have invented new and useful Improvements in Hose-Supporters, of which the following is a full, clear, and exact description.

My invention relates to hose supporters, and particularly to the kind employing straps secured at their upper ends to the waist-band of the trousers of the wearer or to his belt, and provided at their lower ends with suitable clasps to which the socks are attached. Hose supporters of this kind have been made with transverse bands that surrounded the leg both below and above the knee, but these were made wholly or partly of elastic and would bind and pinch the flesh, and would not automatically conform to the play of the muscles either when the wearer was sitting down or standing up, and had a tendency to roll at the edges and corrugate and dent the flesh.

The objects of my invention are to enable these transverse bands to conform to the shape of the legs both above and below the knee without binding the muscles or pinching into the flesh or preventing the free movement of the knee whether the leg is straight or bent and to retain the supporting straps in their relative positions both inside and outside of the leg without causing discomfort. This I accomplish by the means hereinafter fully described, and as particularly pointed out in the claims.

In the drawings:

Figure 1 shows the outlines of the lower part of the human body and leg and my improved supporter attached thereto.

Fig. 2 is a perspective view of a portion of said supporter, drawn to a larger scale.

Fig. 3 shows a fragment of said supporter showing a modified construction which may be adopted, if desired.

Referring to the drawings, A and B represent the two supporting straps of my improved hose supporter. These are of a length extending from the waist to below the knee, and are made of elastic material and provided at their upper ends with adjusting loops *a* and with clasps of any suitable design for attaching the same to the buttons of the waist band or to a belt or to the ends of a suspender in any suitable manner. Ordinary clasps *c*, *d*, are secured

to loops at the lower ends of straps A and B and terminate opposite the portion of the leg where the upper part of the sock usually ends. One of these straps extends down from the hip along the outside of the leg and the other strap extends from a point approximately in front of the hip-bone, down next the inside of the leg. Just above the knee said straps are connected by a vertically adjustable transverse band of non-elastic material, which is hereinafter referred to as the over-knee band C, and just below the straps are connected by a transverse band D of non-elastic material, hereinafter referred to as the under-knee band.

Over-knee band C between the straps is curved upward and what would be its rear shorter end 5, when the bands surround the leg, extends beyond the outside strap A and is bent upward, and has a non-elastic strap 6 sewed or otherwise secured to its outer surface, which extends beyond said end, substantially as shown. The opposite or front end 7 of this over-knee band is, preferably a little more than twice the length of end 5 and extends laterally in an upwardly direction from strap B for about half its length, and then extends downward at about an angle of fifteen degrees, thus describing an obtuse angle whose vertex points upward. The outer surface of said end 7 is provided near its extremities with a suitable buckle 8 which is engaged by strap 6 when the band is fastened around the leg.

The under-knee band D is curved downward between the supporting-straps and the length of the portion thereof between said straps, is, preferably, slightly longer than the portion of the upper-knee band between the same. The rear end of this under-knee band, or end thereof extending beyond strap A, has a non-elastic strap 10 secured to its outer surface that extends beyond the extremity of the same. The opposite front end of this lower-knee band extends beyond the inner strap a distance corresponding to about three-fourths the length of the superposed end 7 of the upper-knee band and curves upward rather sharply so that when flattened, as shown in Fig. 2 of the drawings, it extends substantially parallel to the portion of end 7 of said over-knee band nearest supporting strap B.

When the supporting-straps are attached at their upper ends to the means from which

it is designed they should be suspended, and clasps *c*, *d*, on their lower ends are attached to the opposite side of the upper ends of the sock, said bands are made to surround 5 the leg both above and below the knee and their ends are then secured together; said ends do not tightly embrace the leg and both the front and rear muscles of the leg, above and below the knee, have free play, 10 and the said bands do not interfere with the wearer either when bending the knee or straightening out the leg or standing or sitting down.

In order to permit the distance between 15 the over-knee band and the under-knee band to be adjusted to accommodate persons with large or small knees, I prefer to attach the supporting-straps to the over-knee band by means that will permit the over-knee band to be adjusted either up or down thereon. This I accomplish by means of button-holes 20 12 made in the said band and buttons 13 sewed or otherwise secured to the straps, substantially as shown in Fig. 2 of the drawings. The supporting-straps, however, 25 may be either immovably attached to the upper knee band or adjustably attached thereto without departing from the spirit of my invention.

30 What I claim as new is:—

1. A hose supporter comprising two supporting-straps, devices secured to their upper ends for suspending the same from the clothing, clasps on their lower ends for 35 fastening the hose thereto, a transverse over-knee band, a transverse under-knee band connecting said supporting straps, and separable means for adjustably connecting together the ends of said bands extending 40 beyond said straps; said over-knee band being curved upward between said straps.

2. A hose supporter comprising two supporting-straps, devices secured to their upper ends for suspending the same from 45 the clothing, clasps on their lower ends for fastening the hose thereto, a transverse over-knee band, a transverse under-knee band connecting said supporting straps, and separable means for adjustably connecting 50 together the ends of said bands extending beyond said straps; said over-knee band being curved upward between said straps, and said under-knee band being curved downward between said straps.

55 3. A hose supporter comprising two supporting-straps, devices secured to their upper ends for suspending the same from the clothing, clasps on their lower ends for

fastening the hose thereto, a transverse over-knee band, a transverse under-knee band 60 connecting said supporting-straps, and separable means for adjustably connecting together the ends of said band extending beyond said straps, said under knee band being curved downward between said straps and 65 having one end extending beyond the adjacent strap and curved upward.

4. A hose supporter comprising two supporting-straps, devices secured to their upper ends for suspending the same from 70 the clothing, clasps on their lower ends for fastening the hose thereto, a transverse over-knee band, a transverse under-knee band connecting said supporting-straps, and separable means for adjustably connecting together the ends of said band extending beyond said straps; said over-knee band being 75 curved upward and having one end approximately twice as long as the other end and describing, substantially, an obtuse angle 80 the upwardly pointed vertex of which is about midway its length and said under-knee band being curved downward between said straps and having its end below the said bent end of the over-knee band extending 85 beyond the adjacent strap curved upward.

5. A hose supporter comprising two supporting straps, devices secured to their upper ends for suspending the same from 90 the clothing, clasps on their lower ends for fastening the hose thereto, a transverse over-knee band, a transverse under-knee band connecting said supporting-straps, and separable means for adjustably connecting together the ends of said band extending beyond 95 said straps; said over-knee band being curved upward between said straps and having its ends extend beyond the adjacent strap twice the distance its opposite end extends beyond the opposite strap and describing substantially an obtuse angle the 100 upwardly pointed vertex of which is about midway its length, and said under-knee band having its end below the angle shaped end of the over-knee band extend beyond 105 said strap a distance less than said angle shaped end and curved upward, and between said straps being curved downward.

In witness whereof I have hereunto set my hand this 26th day of October, 1918. 110

NETTIE M. HURD.
